UNITED STATES PATENT OFFICE.

VICTOR E. SODERQUIST, OF MARSHALLTOWN, IOWA, AND LLOYD E. MAPLETHORPE, OF ROCK ISLAND, ILLINOIS.

SAFE-PROTECTING DEVICE.

Application filed December 4, 1922. Serial No. 604,956.

To all whom it may concern:

Be it known that we, VICTOR E. SODERQUIST and LLOYD E. MAPLETHORPE, citizens of the United States, residing at Marshalltown and Rock Island, respectively, in the counties of Marshall and Rock Island and States of Iowa and Illinois, respectively, have invented a certain new and useful Safe-Protecting Device, of which the following is a specification.

The object of our invention is to provide a safe or vault protecting device of simple, durable, and comparatively inexpensive construction.

More particularly, our invention relates to a container having a gas therein, which is designed to be placed in a safe or vault so that when the safe or vault is broken open, the container will be broken and the gas permitted to escape.

Still another object is to provide a novel arrangement for holding the gas in a container so that the device may be easily shipped and carried from place to place without much danger.

With these and other objects in view, our invention consists in the construction, arrangement and combination of the various parts of our device, whereby the objects contemplated are attained, as hereinafter more fully set forth, pointed out in our claim, and illustrated in the accompanying drawings, in which:

Figure 1 is a perspective view of our protecting device.

Figure 2 is a central, sectional view taken through the same.

Figure 3 is a detail, sectional view taken on the line 3—3 of Figure 1.

Figure 4 is a sectional view taken on line 4—4 of Figure 2; and

Figure 5 is a perspective view of one corner of the device.

In the accompanying drawing, I have used the reference numeral 10 to indicate generally, a container which is provided with an open end. Placed within the container, against each of the walls thereof, is the corrugated paper backing 11. The purpose of the paper backing 11 will be hereinafter more fully set forth.

Received within the container 10 are a number of bottles 12. The bottles 12 are filled with a non-poisonous gas 13. A rub-

ber stopper 14 is placed in the neck of the bottle for sealing the gas within the bottles 12. After the rubber stopper 14 has been placed in the bottle, it is covered with a sealing wax 15 so as to insure against any possible escape of the gas from the bottles.

On the bottom of the container 10 is placed some cotton packing 16 so that the bottles 12 may rest thereon. The normally upper ends of the bottles are placed against the cotton as clearly shown in Figure 2 of the drawing.

Between each of the bottles, for preventing their rubbing against each other, we provide a felt packing 17. The bottles 12 are thus securely packed into the container 10 so as to prevent their accidental breaking.

The upper ends of the side walls of the container are bent towards each other so as to provide short flanges 18. The upper edges of the end walls of the container are also bent toward each other for providing short flanges 19.

A glass 20 is slid in below the flanges 18 and 19. One of the flanges 19 is not bent into position until after the glass 20 has been properly positioned. After the glass 20 is in position, one of the flanges 19 is bent over for securely holding the glass.

From the construction of the parts just described, it will be seen that the gas containing bottles 12 are securely packed in the container 10 with the bottom ends resting against the glass 20.

The entire device may be placed with the glass side down between the inner and outer walls of a vault, so that when the outer door is blown open, the glass 20 will be broken and bottles containing the gas will be broken for permitting the gas to escape. The entire device may be placed in a safe so that when it is broken open the gas containing bottles will also be broken.

The gas used is a non-poisonous gas which will not any way affect any of the papers in the vault, and yet will cause the burglars to be overcome for sometime.

In this connection it may be mentioned that the device may be supported by hooks or any other suitable means, on the inner side of the vault door itself.

The entire arrangement of the device is such that it can be shipped from place to

place, and handled with a minimum amount of danger.

The glass 20 and the bottles 12 being frangible will permit them to become easily broken and crushed due to the blowing open of the vault or safe.

Our device will be very effective for overcoming the burglars and preventing their removing any of the contents of the safe or vault, and at the same time cause them to be "laid out" for sometime.

Some changes may be made in the construction and arrangement of the various parts of our device, without departing from the real spirit and purpose of our invention and it is our intention to cover by our claim, any modified forms of structure or use of

mechanical equivalents, which may be reasonably included within its scope.

We claim as our invention:

In a device of the class described, a container open at one end having in-turned flanges at its edges at its open end, a plurality of frangible bottles in said container with their bottoms adjacent to the open end thereof adapted to contain a gas, a frangible plate held between the bottom of said bottles and said flanges, and means for cushioning the bottles at their tops and sides from the casing and from each other.

Des Moines, Iowa, August 23, 1922.

VICTOR E. SODERQUIST.
LLOYD E. MAPLETHORPE.
